DENTAL CABINET

James D. Floria, Milwaukee, Wis., assignor to Hamilton Manufacturing Company, Two Rivers, Wis., a corporation of Wisconsin

Application August 10, 1956, Serial No. 42,572

Term of patent 14 years

(Cl. D24—1)

Figure 1 is a perspective view of a dental cabinet or similar article showing my new design;

Figure 2 is a side view thereof showing the medicine compartment cover in raised position; and

Figure 3 is a cross-section through a corner of the cabinet taken on the line 3—3 of Figure 1.

The characteristic features of my design reside in the inwardly directed taper on the outer edges of the side panels and the vertically aligned handles having the configuration as shown.

I claim:

The ornamental design for a dental cabinet or similar article, substantially as shown and described.
